SLIDING DRAFT LUG FOR RAILWAY CARS

Bertil E. Peterson, Chicago, Ill., assignor to Cardwell Westinghouse Company, a corporation of Delaware

Application June 28, 1954, Serial No. 439,799

19 Claims. (Cl. 213—22)

The present invention relates to a sliding draft lug for railway cars, and, more particularly, to a sliding front draft gear lug for use with the tandem draft gear disclosed in my co-pending application Serial No. 399,970, filed December 23, 1953, of which this application is a continuation-in-part.

My above-mentioned co-pending application discloses a railway car draft and buffering arrangement including center sills, front and rear draft lugs or stops fixed to the sills, a vertical yoke connected by a draft key to a coupler shank provided with a front follower, and a draft gear within the yoke in the usual manner and adjacent the front follower. According to the teachings of said co-pending application, the draft gear lugs or stops that take the thrust from the draft gear to the center sills are located inwardly beyond the bolster, and an inner or back draft gear is associated with them and a secondary or rear follower. The bolster center filler casting is modified to provide spaced passages or passageways, one at either side of the center pin opening, to receive a pair of thrust members acting as columns between the rear of the casing for the draft gear and the rear or secondary follower. For a more detailed description, one may refer to my above-mentioned application, the complete disclosure of which is hereby incorporated by reference in the interests of brevity.

The principal object of this invention is to provide a railway draft and buffering arrangement including draft gear in tandem wherein conventional draft gear couplers and yokes may be employed with facility.

A further object of this invention is to provide means for properly balancing and supporting conventional couplers used in connection with tandem draft gear.

According to the present invention, the railway car center sills extend short of the end of the car, and a pair of rigid channel members is fixedly mounted on the sides of the center sills at a distance apart that is greater than the distance between the center sills. Said channel members have their inner ends joined to the respective ends of the center sills and extend to a point adjacent the end of the car. A second set of rigid channel members is slidably mounted within the first set and in alignment with the center sills, respectively. The second set of channel members carries a draft key which connects the coupler shank, that extends inwardly between the second set of channel members to a yoke co-operating in the usual manner with the first or outer draft gear. The front follower bears against the first or outer draft gear in buff with the force being transmitted by means of the thrust members to the rear draft gear and rear lugs or stops, and in draft the follower bears against lugs or abutment means on the second pair of channel members, comprising front draft gear lugs or stops, which are limited in their outward movement by further lugs or abutment means co-operating with lugs or abutment means formed on the fixed pair of channel members. A coupler carrier is fixed between the second set of channel members on which the coupler shank may be properly

2

supported and balanced regardless of its position with respect to the fixed channel members and the center sills, of which the fixed channel members form a part.

From the foregoing it will be obvious that the present invention provides substantial advantages over prior practices. For example, conventional draft gear couplers and yokes may now be employed in connection with a tandem draft gear arrangement that provides a marked increase in capacity to absorb buffering shocks, and yet the couplers are supported so as to avoid undesirable sag.

In addition to the foregoing, it is an object of the present invention to provide a draft and buffering structure of the character defined which is economical of manufacture, capable of ready attachment to conventional railway vehicles and capable of use with substantially all types of draft vehicles.

Other objects and advantages of the present invention will become apparent in the following description of a preferred embodiment thereof, in which:

20 Fig. 1 is a horizontal section through familiar parts of a freight car, showing the draft and buffering or cushion elements thereof in draft position;

Fig. 2 is similar to Fig. 1, showing the draft and buffering or cushion elements in cushioning or buffering position;

25 Fig. 3 is a cross-sectional view along line 3—3 of Fig. 1, with parts shown in elevation;

Fig. 4 is a cross-sectional view along line 4—4 of Fig. 1;

Fig. 5 is a perspective view of the outer end of the center sills illustrating my invention as applied thereto;

30 and Fig. 6 is a view similar to that of Fig. 5, with parts broken away for clarity of illustration.

Referring more particularly to Figs. 1 and 2, reference numeral 10 indicates center sills that are fixed to the

35 bottom of a railway car in the conventional manner. Also shown are front and rear draft gear lugs or stops 11 and 12, a vertical yoke 13 connected to a coupler shank 14 by draft key 15 in the positions they assume in draft with the coupler horn 16 spaced from the striking plate 17

40 (see Figs. 5 and 6) and the front follower 18 against the front gear lugs 11 (in the position of Fig. 1). Reference numeral 19 indicates a familiar form of draft gear including friction plates 19^a, supported by draft gear carrier

20 and in the usual relation within the yoke 13.

45 As described in my aforementioned application, the draft gear lugs or stops, indicated at 12, that take the thrust from the draft gear to the center sills, are positioned inwardly beyond the bolster 21, and an inner or back draft gear 22, including friction plates 22^a, is

50 associated with them and a rear or secondary follower 23. The bolster center filler casting 25 is provided with spaced passages or passageways 26, one at either side of the center pin opening 27, to receive a pair of thrust members 28 acting as columns between the rear of the

55 casing for the draft gear 19 and the rear or secondary follower 23. Hardened steel wear blocks (not shown) are positioned in the bottoms of the passageways to support the thrust members 28 at rest and in their back and forth movement during the operation of the draft gear mechanism. The bolster center filler may be welded or otherwise fixed to the center sill structure as desired.

60 In the present invention the outer ends of the sills 10 do not extend to the end of the car, but instead terminate a distance somewhat short of the end, and rigid

65 channel members or bars or plates 34, which may be of other configuration, are fixedly mounted on either side of the sills and extend from the sills to a point adjacent the end of the car.

66 Diagonal tie plates 36 rigidly connect the channel members 34 to the ends of the sills 10 and die bar 29 (see Figs. 5 and 6) spaces the ends of members 34 apart from each of other; in effect the channel members 34

comprise outer ends of the sills that are offset outwardly from each other to provide an enlarged space 31 therebetween. Slidably mounted within the horizontal sides of the channel members 34, on hardened steel wear plates or bars 33 (see Fig. 3), are the rigid channel members or bars or plates 38 (which also may be of other configuration) preferably aligned with the center sill flanges 40, as shown in Figs. 1 and 2. The front draft gear lugs or stops 11, together with strengthening ribs 37 (see Fig. 6) are fixed to the channel members 38, 10 and said channel members carry the draft key 15 (in holes or perforations 41) for movement therewith. The draft key extends through the channel members 34, which have slots 42 provided therein to allow for relative movement of the key. Lugs or abutment means 44, fixed to the inside surfaces of channel members 34, 15 co-operate with lugs or abutment means 46 fixed to the outside surfaces of the channel members 38 (see Figs. 1 and 6) to limit the outward movement of channel members 38.

As shown in Figs. 3 and 6, the channel members 34 are provided with rigid members 50 forwardly of abutment means 44, which may be welded thereto, as at 51, to act as spacers and reinforcing or strengthening members, and channel members 38 are provided with similar members 53 (see Fig. 6). The draft key may be provided with a conventional head 54 and pin 56 to insure that it remains in the position illustrated, and the top flanges of the channel members 34 may be fixed, as by welding, to the plate 58, to further strengthen the structural arrangement. As illustrated most clearly in Figs. 5 and 6, a coupler carrier 60 is secured between the channel members 38 by any suitable means, such as by bolts 62.

It has been found that the sliding channel arrangement, together with the coupler carrier forming a part thereof, allows one to correctly balance and support conventional draft gear couplers without modification of the couplers and yokes employed.

In operation, upon receiving a buffing shock, the coupler shank 14 is moved to the right in Fig. 1, transmitting the force of the shock to the front or primary follower 18, thence to the front draft gear 19, thence to the columns or thrust members 28, thence to the secondary follower 23, thence to the rear draft gear 22, and finally to the rear lugs or stops 12. During the course of movement the draft gears function in the usual manner to allow travel, and during travel to absorb and dissipate the energy of the shock and spread out the force of impact. In the illustrated structure, the draft key 15, upon buffing shock, urges the channel members 38 inwardly of the car or to the right in Fig. 1, and separates the abutment means or lugs 46 from the abutment means or lugs 44 (see Fig. 2).

Upon release the draft gears act according to their design to return all moving parts to the original position as shown in Fig. 1.

In the draft the coupler shank 14 moves outwardly of the car or to the left of Figs. 1 and 2. The draft key 15 operates in conventional manner to pull yoke 13 and gear 19 therein against follower plate 18, said follower abutting lug 11 which resists motion due to contact of lug 46 with fixed lug 44.

It should be noted that the coupler carrier 60 provides a support which is substantially fixed with respect to the coupler shank 14, so that during all possible positions of the shank it remains properly balanced and supported, thus avoiding undesirable sag in one or all of its possible positions. The relative movement between the coupler shank 14 and channel members 38 (and the coupler carrier 60 carried thereby) will be governed by the play between the draft key 15 and the channel members 38.

The foregoing description and the drawings are given merely to explain and illustrate my invention, and the

invention is not to be limited thereto, except in so far as the appended claims are so limited since those skilled in the art who have my disclosure before them will be able to make modifications and variations therein without departing from the scope of the invention.

I claim:

1. In a railroad car, center sills having their outer ends offset outwardly from each other to provide an enlarged space therebetween, sliding bars mounted on each side of said enlarged space for movement longitudinally of the sills, a draft key carried by said bars, a coupler shank, a yoke connected to said coupler shank through said key, a follower carried within said space, cushioning means carried adjacent and inwardly of said follower, abutment means carried by said center sills for limiting outward movement of said bars, and draft gear lugs carried by said bars for limiting outward movement of said follower.
2. In a railroad car including spaced apart center sills, 20 a coupler shank, a yoke connected to the coupler shank by a draft key, a front follower, cushioning means mounted within the yoke and adjacent the follower, and front draft gear lugs adjacent the follower, the improvement comprising a pair of rigid members fixedly secured to the car adjacent the end thereof and spaced apart a distance greater than the distance between the center sills, said members forming the outer ends of the center sills, a pair of plates slidably mounted between said rigid members for movement longitudinally of the center sills, said front draft gear lugs being fixed to said plates, said follower being disposed between said lugs and said compression means, and abutment means carried by said rigid members for limiting outward movement of said plates.
3. A draft device comprising an elongated rigid enclosure having an outer end of greater width than the remainder of the enclosure with the outer end being partially defined by laterally spaced apart substantially vertical side walls, laterally spaced apart sliding plates mounted adjacent the outer end of each side wall, a draft key carried by said plates, a coupler shank, a yoke connected to said coupler shank by said key, compression means carried within the yoke, follower means cooperating with the end of said coupled shank, draft gear lugs carried by said plates for engagement with said follower means on outward movement of said shank, said follower means engaging said compression means on inward movement thereof, and abutment means carried by said plates for engagement with said side walls near their outer ends to limit outward movement of said plates.
4. In a railroad car, center sills having their outer ends offset outwardly from each other to provide an enlarged space therebetween, sliding bars mounted on each side of said enlarged space for movement longitudinally of the sills, a draft key carried by said bars, a coupler shank, 40 a follower carried within said space, draft gears spaced apart in tandem, one of said draft gears being carried within said yoke and adjacent said follower, rigid means extending between said draft gears and being mounted for sliding movement therebetween, abutment means carried by said outer ends of said center sills for limiting outward movement of said bars, and draft gear lugs carried by said bars for limiting outward movement of said follower.
5. In a railroad car, center sills having their outer ends offset outwardly from each other to provide an enlarged space therebetween, sliding bars mounted on each side of said enlarged space for movement longitudinally of the sills, a draft key carried by said bars, a coupler shank, a yoke connected to said coupler shank through said key, a front follower, a pair of draft gears spaced apart in tandem, one of said draft gears being carried within said yoke and adjacent said front follower, a bolster filler between said draft gears and having spaced passageways, thrust members in the passageways in thrust relation to

the draft gears, rear draft gear lugs fixed to said center sills and co-operating with the other of said draft gears, abutment means carried by said outer ends of said center sills for limiting outward movement of said bars, and front draft gear lugs carried by said bars for limiting outward movement of said follower.

6. In a railroad car, center sills extending short of the end of the car, a first pair of channels fixedly mounted on the sides of the center sills and extending between the ends of said center sills and the end of the car, said channels being disposed to provide a relatively wide space therebetween, and having their short sides opposed to each other, a second pair of channels each mounted for sliding movement within the short sides of the first pair of channels, abutment means carried by each channel of said second pair of channels for engagement with said first-mentioned abutment means to limit outward movement of said second pair of channels, and a coupler carrier fixed between said second pair of channels.

7. In a railroad car, center sills extending short of the end of the car, a first pair of channels fixedly mounted on the sides of the center sills and extending between the ends of said center sills and the end of the car, said channels being disposed to provide a wider space therebetween than the space between said center sills, said channels having their short sides horizontally disposed and opposed to each other, a second pair of channels each mounted for sliding movement within the short sides of the first pair of channels, a draft key carried by said second pair of channels, a coupler shank disposed between said second pair of channels, a yoke connected to said coupler shank through said key, a follower co-operating with said coupler shank, compression means mounted within said yoke, abutment means carried by said first pair of channels, abutment means carried by said second pair of channels for engagement with said first-mentioned abutment means to limit outward movement of said second pair of channels, and draft gear lugs carried by said second pair of channels for limiting outward movement of said follower.

8. In buff cushioning apparatus, draft gears spaced apart in tandem, a bolster filler between the draft gears and having spaced passageways, thrust members in the passageways in thrust relation to the draft gears, a coupler shank, a yoke connected to the coupler shank by a draft key, a follower co-operating with the end of the coupler shank to transmit buff forces from said shank to the outer of said draft gears, and rigid members mounted adjacent said follower for limited longitudinal movement, said follower engaging said rigid members in draft, said rigid members limiting the outward movement of said coupler shank.

9. In buff cushioning apparatus, draft gears spaced apart in tandem, thrust members extending therebetween in thrust relation to the draft gears, a coupler shank, a yoke connected to the coupler shank by a draft key, a follower co-operating with the end of the coupler shank to transmit buff forces from said shank to the outer of said draft gears, and rigid members mounted adjacent said follower for limited longitudinal movement, said follower engaging said rigid members in draft, said rigid members limiting the outward movement of said coupler shank.

10. In buff cushioning apparatus, draft gears spaced apart in tandem, thrust members extending therebetween in thrust relation to the draft gears, a coupler shank, a yoke connected to the coupler shank by a draft key, a follower co-operating with the end of the coupler shank to transmit buff forces from said shank to the outer of said draft gears, and rigid bars mounted either side of said coupler shank and adjacent said follower for limited longitudinal sliding movement, said bars having a coupler carrier fixed therebetween for supporting said coupler shank, said follower engaging said rigid bars in draft, said rigid members limiting the outward movement of said coupler shank.

11. In a railway car having cushioning apparatus of the

type adapted for extended travel in buff mounted between spaced center sills and adapted to receive buff forces from a coupler shank, front stop lugs in slidable engagement with said center sills, said lugs having first abutment means cooperating with abutment means on said center sills to limit the outward travel of said cushioning apparatus and second abutment means engaged by the inward movement of the coupler shank to move the said lugs inwardly.

12. In a railway car having cushioning apparatus of the type adapted for extended travel in buff mounted between spaced center sills having their outer ends offset laterally from each other to provide an enlarged space therebetween and adapted to receive buff forces from a coupler shank, front stop lug supporting means in slidable engagement with said outer ends, and front stop lugs rigid with said supporting means, said supporting means having a first abutment surface cooperating with abutment means on said center sills to limit the outward travel of said cushioning apparatus and having a second abutment surface having a first portion responsive to the inward movement of the coupler shank to move the front stop lugs inwardly from their outer limit position and a second portion responsive to the release movement of the cushioning apparatus to return the front stop lugs to their outer limit position.

13. In a railway car having cushioning apparatus of the type adapted for extended travel in buff mounted between spaced center sills and adapted to receive buff forces from a coupler shank and draft forces from a yoke connected to said shank by a draft key, front stop lugs in slidable engagement with said center sills, said lugs including first abutment means cooperating with fixed abutment means on said center sills to limit the outward travel of said cushioning apparatus and second abutment means engaged by the inward movement of the draft key to slide the said lugs inwardly whereby conflict between the yoke and said lugs is avoided.

14. In a railway car having cushioning apparatus of the type adapted for extended travel in buff mounted between spaced center sills and adapted to receive buff forces from a conventional coupler shank and draft forces from a conventional yoke connected to said shank by a draft key in a conventional manner, the improvement wherein the outer ends of said center sills are offset laterally from each other to provide an enlarged space and said outer ends carry fixed abutment means, front stop lugs in slidable engagement with said outer ends, said lugs including first abutment means cooperating with said fixed abutment means to limit the outward travel of said cushioning apparatus and second abutment means engaged by the inward movement of the draft key to slide said lugs inwardly and prevent conflict between the yoke and said lugs.

15. In a railway car having cushioning apparatus of the type adapted for extended travel in buff mounted between spaced center sills and adapted to receive buff forces from a coupler shank, a coupler carrier iron in slidable engagement with said center sills, and means engaged by the inward movement of the coupler shank to move the carrier iron inwardly a substantially corresponding distance.

16. In a railway car having cushioning apparatus of the type adapted for extended travel in buff mounted between spaced center sills and adapted to receive buff forces from a coupler shank, a coupler carrier iron is slidably engagement with said center sills, and means engaged by the inward movement of the coupler shank to move the carrier iron inwardly from its neutral position a substantially corresponding distance and engaged by the release movement of the cushioning apparatus to return the carrier iron to its neutral position.

17. In a railway car having cushioning apparatus of the type adapted for extended travel in buff mounted between spaced center sills and adapted to receive buff forces from a coupler shank, carrier iron supporting means in slidable engagement with said center sills, and a carrier

iron rigid with said supporting means, said supporting means having a first portion thereof engaged by the inward movement of the coupler shank to move the carrier iron inwardly from its neutral position a substantially corresponding distance and a second portion engaged by the release movement of the cushioning apparatus to return the carrier iron to its neutral position.

18. In a railway car having cushioning apparatus of the type adapted for extended travel in buff mounted between spaced center sills and adapted to receive buff forces from a coupler shank, the improvement wherein said center sills include fixed abutment means and front stop lugs are slidably mounted on said center sills with each lug including a first abutment surface inward of said abutment means to cooperate therewith and limit outward travel of said cushioning apparatus and a second abutment surface engaged by the inward movement of the coupler shank to move the said lugs inwardly.

19. In a railway car having cushioning apparatus of the type adapted for extended travel in buff mounted be-

tween spaced center sills and adapted to receive buff forces from a coupler shank, supporting means mounted in slideable engagement with said center sills and carrying front stop lugs and a carrier iron, said supporting means having a first portion thereof engaged by the inward movement of the coupler shank to move the supporting means inwardly a corresponding distance and a second portion engaged by release movement of the cushioning apparatus to move the supporting means outwardly, said center sills having fixed abutment means limiting outward movement of said supporting means.
